[57] CLAIM

The ornamental design for a curved front, air-curtain merchandiser, as shown and described.

DESCRIPTION

FIG. 1 is a perspective view;
FIG. 2 is an enlarged right side elevational view; the left side elevational view being a mirror image;
FIG. 3 is an enlarged front elevational view;
FIG. 4 is an enlarged rear elevational view;
FIG. 5 is an enlarged top plan view;
FIG. 6 is an enlarged bottom plan view.

The broken line showing is for illustrative purposes only and forms no part of the claimed design.
